[57] CLAIM

The ornamental design for a high speed watercraft, as shown and described.

DESCRIPTION

FIG. 1 is a top and front perspective view of a high speed watercraft showing my new design;

FIG. 2 is a right side elevation view thereof, the left side elevation view being a mirror image;

FIG. 3 is a top plan view thereof;

FIG. 4 is a bottom plan view thereof;

FIG. 5 is a front elevation view thereof; and,

FIG. 6 is a rear elevation view thereof.

FIG. 6

FIG. 5

FIG. 4
